UNITED STATES PATENT OFFICE

HARRY G. NORWOOD, OF BALTIMORE, MARYLAND, ASSIGNOR TO POSITIVE LOCK WASHER COMPANY, OF NEWARK, NEW JERSEY

SPRING NUT-LOCK WASHER

Application filed August 10, 1928. Serial No. 384,357.

This invention relates to an improved form of spring lock washer, particularly adapted for use for heavy work or where high pressures are applied to the washers, such as in railroad work in bolting ties together, and for other heavy duty work.

It is the principal object of my invention to provide a spring lock washer which will give at least spring effects in two distinct ways—first, by the offset of the split ends of the washer, and second, due to the shape or cross-sectional form of the washer stock.

Another object of my invention is to provide a spring washer which will take a very high pressure and still retain its resilience and ability to take up for stretch in the bolt.

Another object of my invention is to provide a spring washer which cannot be distorted, by the tension of the nut, beyond its elastic limit or ability to maintain its spring effect to hold the joint tight.

My invention will be readily understood by reference to the annexed drawing, wherein:

Figure 1 shows an assembled view of one form of the washer as it is just being engaged by the nut.

Figure 2 is a plan view of the face of one form of the washer.

Figure 3 is vertical sectional view through Figure 2.

Figure 4 is a plan view of that form of the washer shown in Figure 1.

Figure 5 is a side elevation of Figure 4.

Figure 6 is a vertical sectional view through Figure 4.

In the two forms of washers shown in the drawing, the washers are preferably made of drawn or rolled stock which is provided with grooves 1 and 2 that extend from end to end of the stock. The grooves 1 and 2 are separated by an annular abutment 3 which in the form shown in Figures 1, 4, and 6, is substantially in the same plane 4 as the edges 5 and 6 of the washer.

In the form shown in Figures 2 and 3, the abutment 3 projects somewhat beyond the plane of the edges 5 and 6, as indicated by the space 7, but in either form, the washer is substantially in the shape of the numeral

3. It is to be understood that where the washer is made from drawn or rolled strip stock, this is rolled up in a spiral manner, as is the usual practice in the making of lock washers, and cut off as indicated at 8. It is also to be noted that the stock is provided with a depression or groove 12 opposite the abutment 3, and as will be seen from Figure 1, when pressure is applied to the nut 10 on the bolt 11 to place the washer against the work 9, the pressure tends to spread the edges 5 and 6, thereby putting the washer under tension, and this tension will increase until the depression 12 has been substantially obliterated. The larger amount of the additional pressure applied by the nut 10, is then taken by the abutment 3; or in other words, the abutment 3 prevents the additional tension applied to the nut 10 from spreading the edges 5 and 6 beyond the elastic limit of the material, so the washer will maintain its spring effect, thereby holding the joint tight, and at the same time prevent the washer from becoming broken due to the strain applied by the nut.

In the form shown in Figure 3, the abutment 3 has been shown somewhat sharper than that shown in Figures 1 and 6. In this form of washer, the parts 5 and 6 are bent downward or spread about the annular abutment 3 until the edges 5 and 6 engage the work, when the action becomes substantially the same as in the form shown in Figure 1. The form of washer shown in Figure 3, is somewhat more resilient and has a greater spring effect, than that shown in Figure 1, but the claims are intended to cover both forms.

While I prefer to make the washer from drawn or rolled stock, it may be formed in suitable dies and for some classes of work, the washer need not be split as shown in the drawing.

Having thus described my invention, what I claim is:

1. A spring nut lock washer having a 3-shaped transverse cross-section taken on any radius of the washer.
2. A spring nut lock washer formed spirally and cut to leave a split, the stock having

substantially a 3-shaped cross-section from end to end.

3. A spring nut lock washer having a split and the ends adjacent the split offset a predetermined amount in opposite directions to give a certain spring effect, said washer having a further spring effect by reason of its cross-sectional shape which is substantially like the numeral 3.
- 10 4. A spring nut lock washer having a pair of grooves on one face thereof and an abutment between said grooves, said abutment having a depth so as to come into engagement before the edges formed by the grooves.
- 15 5. A spring nut lock washer formed spirally and having a pair of spaced grooves on one face with an abutment therebetween, and a recess in the other side of the stock opposite said abutment for the purposes described.
- 20 6. A spring nut lock washer having a pair of grooves on one face thereof and an abutment between said grooves, said abutment having a depth so as to come into engagement at least as soon as the edges formed by the grooves, the material on the nut side of the washer opposite the abutment being removed whereby initial pressure of the nut is applied on opposite sides of the abutment as 25 and for the purposes described.
- 25 7. A spring nut lock washer having the material of the washer so formed as to have substantially an annular fulcrum between the inner and outer edges of the washer, and 30 the material opposite the fulcrum removed so pressure by the nut initially tends to stress the material about the fulcrum and finally under high pressure from the nut, the fulcrum limits the stress on said edges for the 35 purpose described.
- 40 In testimony whereof, I affix my signature.
HARRY G. NORWOOD.
